(57) **CLAIM**

The ornamental design for a cutting tool, as shown and described.

DESCRIPTION

FIG. 1 is a front view of a cutting tool showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a cross sectional view taken along line 7-7 of FIG. 1;

FIG. 8 is a cross sectional view taken along line 8-8 of FIG. 1;

FIG. 9 is a front perspective view thereof;

FIG. 10 is a rear perspective view thereof; and,

FIG. 11 is a front perspective view thereof, shown in an environment of use.

The broken lines shown in the referential views represent portions that form no part of the claimed design.

1 Claim, 6 Drawing Sheets
